ELECTROMAGNETICALLY OPERATED TYPEWRITER

Abraham E. Auerbach, La Mesa, Calif., assignor to Leon Fine & Associates, Highland Park, Ill.

Application April 30, 1956, Serial No. 581,421

16 Claims. (Cl. 197—14)

This invention is concerned generally with a typewriter, and more specifically with an electromagnetically operated typewriter.

So-called office typewriters, as distinguished from portables, are divided generally into three classes. These comprise the conventional typewriter, the "noiseless" typewriter, and the electric typewriter. The conventional office typewriter offers the advantages of lowest cost, and relatively lightweight. Such machines also can be used where no electricity is available, but this is a negligible consideration in modern offices. However, conventional typewriters are subject to several drawbacks. Considerable physical effort is necessary on the part of the typist to operate the machine. The type bars are thrown against the ribbon and paper, and this causes considerable noise. Furthermore, there are considerable physical shocks present. These features cause the machine to get out of adjustment, and to wear out relatively rapidly. Furthermore, they fatigue the typist unduly.

The "noiseless" machines are provided with a lever action such that the type bar is thrown near the ribbon, and the mechanism then operates the type bar to move the type face against the ribbon with somewhat of a pressing motion. This reduces noise substantially, but does not completely eliminate it. This type of machine is somewhat heavier than the conventional machine, and it is more expensive. Somewhat more effort may be required on the part of the typist, and although the shocks are lessened, thereby decreasing wear on the mechanism, the mechanism is more complicated, and repairs or adjustments are likely to be more expensive.

Electric typewriters require little physical effort for operation, can type at a slightly higher speed, produce uniform typing impressions, and can make a large number of uniform carbon copies. However, maintenance of electric typewriters is likely to be relatively expensive, and the initial cost is substantially higher than conventional or "noiseless" machines. There is no "touch" to an electric typewriter, since the slightest depression of a key causes a typing operation to be completed automatically. This is undesirable to many typists. The continuously running motor of present electric typewriters often is noisy, or may become noisy with age, and may be left running accidentally for long periods, thereby wasting power. Furthermore, should two keys be depressed simultaneously through inadvertence, the corresponding type bars are likely to be thrown into violent collision and thereby damaged. Electric typewriters also are considerably heavier than the conventional and "noiseless" machines.

It is the general object of this invention to produce a typewriter eliminating substantially all the disadvantages of previous machines as set forth above.

More specifically, it is an object of this invention to provide a typewriter operable with a degree of silence never before achieved, and specifically wherein the type face is pressed against the ribbon in the printing operation.

2

Another object of this invention is to provide a typewriter requiring substantially no more physical effort than the present electric typewriter, but retaining the touch of conventional machines.

It is an object of this invention to provide a simplified typewriter of relatively lightweight construction, thereby facilitating portability, reducing the cost of manufacture, and reducing wear and maintenance.

More specifically, it is an object of this invention to provide a typewriter wherein all printing stresses are confined to the type heads, thereby reducing shock and vibration and contributing to ease of typing and to longevity of the machine.

A further object of this invention is to provide an electromagnetically operated typewriter wherein a single electromagnetic device operates on all type bars.

It is a further object of this invention to provide an electromagnetic typewriter wherein all circuits are keyed by the type bars themselves, thereby eliminating problems of synchronization and linkage adjustment.

It is a further object of this invention to provide a typewriter wherein adjustment can be made to produce uniform carbon copies regardless of the number of such copies, within wide limits.

Still another object of this invention is to provide a typewriter having a single electromagnetic device for making typing impressions, for controlling the carriage release, and for returning the carriage.

Other and further objects and advantages of the present invention will be apparent from the following description when taken in connection with the accompanying drawings wherein:

Fig. 1 is a side view, partially in section, of certain of the operating parts of a typewriter constructed in accordance with the principles of my invention;

Fig. 2 is a view similar to Fig. 1 showing the parts in a different position of operation;

Fig. 3 is a top view of the operating parts shown in Figs. 1 and 2;

Fig. 4 is an electrical wiring diagram illustrating the electromagnetic parts of the invention;

Fig. 5 is a side view on an enlarged scale of a portion of the type head;

Fig. 6 is a side view generally similar to Figs. 1 and 3 and showing a modified form of the invention;

Fig. 7 is a vertical sectional view as taken along the line 7—7 in Fig. 6;

Fig. 8 is a horizontal sectional view taken along the line 8—8 in Fig. 6;

Fig. 9 is a vertical sectional view taken along the line 9—9 in Fig. 6;

Fig. 10 is a side view similar to Fig. 1 and showing a modified form of apparatus;

Fig. 11 is an enlarged side view similar to Fig. 5 and showing a further modification;

Fig. 12 is similar to Figs. 5 and 11 and illustrates a further modification;

Fig. 13 is an electrical wiring diagram used in connection with the device of Fig. 10;

Fig. 14 is a view similar to a part of Fig. 4 and showing an adaptation of the apparatus for operating the carriage advancing mechanism;

Fig. 15 is a view of the electromagnetic mechanism as modified to effect return of the carriage;

Fig. 16 is a view partially in section taken along the line 16—16 of Fig. 15;

Fig. 17 is a side view of the modification of the invention as shown in Fig. 6 adapted for carriage return;

Fig. 18 is a view of the mechanism in Fig. 17 taken substantially along the line 18—18 in Fig. 17; and

Fig. 19 is an enlarged fragmentary view of a portion of Fig. 17 showing the parts in greater detail.

Referring now in greater particularity to the drawings, and first to Figs. 1-4, there will be seen the usual typewriter platen 30 having a sheet of paper 32 in typing position thereon. The typing ribbon 34 is in its accustomed position in front of the sheet of paper 32 and opposite to the platen 30. A series of type bars 36 (only one being shown) of more or less conventional construction is pivotally mounted at 38. Reference hereinafter will be made only to the single illustrative type bar and accompanying parts, and it will be understood that all parts are multiplied, where necessary, in accordance with the necessary number of type bars. More specifically, the type bar 36 has a type head or pallet 40 having a type face 42 thereon adapted to engage the ribbon 34 for forming a typing impression on the paper 32. The type bar is provided with a slug 44 of magnetically susceptible material such as soft iron, and this slug is mounted immediately below the type head or pallet, by means such as the dovetail 46 illustrated. In addition, the slug would be welded or soldered in place once it was determined which size or weight slug was to be used with any given type face. A single stop or rest 48 is provided for all of the type bars to hold them in idle position as shown in Fig. 1.

For each type bar 36 there is provided a key lever 50 pivoted at 52 and having an upturned outer end carrying a key 54 of known construction. A stop or rest 56 is provided beneath the inner end of all of the key levers, and a spring 58 is provided for each key tending to hold the associated key lever against this stop. On the inner end of each key lever 50 there is pivoted a dog or jack 60 at 62, and this dog or jack is urged by a spring 64 against a stop 66 for bearing upwardly beneath a projecting shoulder 67 on the type bar.

Depression of a key 54 and accompanying pivotal movement of the key lever 50 will cause the type bar 36 to be moved upwardly from the position shown in Fig. 1 through the dashed line position of Fig. 2 to the solid line position of Fig. 2 in contact with, or substantially in contact with, the ribbon 34. As the type bar 36 approaches this limited position, the jack or dog 60 pivots against the force of the spring 64 and slides off of the shoulder 67 as is shown in full lines in Fig. 2, thus freeing the type bar for partial return, as to the position shown in dashed lines in Fig. 2. However, the force with which the type bar is moved into proximity with the ribbon 34 is by design not sufficient to make a typing impression, and additional means are employed for this purpose as now will be described.

An upwardly directed, generally C-shaped electromagnet 68 is positioned below and in front of the platen 30. The electromagnet is provided with a pair of pole pieces 70 in proximity to the ribbon 34, and positioned so that the magnetic slug 44 of any type bar will pass between the poles. The poles are beveled as at 72, or otherwise are provided with guides to insure centralization of the slug 44, and hence of the type head or pallet 40 in the event that a type bar should be bent in use. The electromagnet 68 further includes an energizing coil 74 connected in a manner shortly to be described.

A nonmagnetic strut 76 extends across the front of the electromagnet 68, the central portion of the strut being displaced into the plane of the electromagnet, and a resilient strip or leaf spring 78 is mounted on this strut with its upper end projecting toward the space between the poles 70. A roller 80 is carried at the upper end of the resilient strip 78 for engagement with the magnetic slug 44, although it readily could be made engageable with any part of the type bar 36. An insulated switch actuator 82 is carried by the resilient strip 78 on the back side thereof, and switch contacts 84 carried by resilient arms 86 70 insulatedly supported from the strut 76 are forced into engagement as shown in Fig. 2 when the resilient strip 78 is deflected by engagement of the slug 44 against the roller 80.

The electrical circuit as shown in Fig. 4 includes a full 75

wave bridge rectifier 88 connected to a flexible cord or wire 90 having a plug (not shown) thereon for insertion in the usual electrical outlet. The positive side of the rectifier is connected to a junction point 92, while the negative side is connected to a bus 94. The bus 94 is connected to one end of the coil winding 74, and the other end of the coil winding is connected to the fixed contact 96 of a relay 98. The relay includes a coil 100 and core 102, toward which an armature 104 is attracted against the force of a spring 106. The armature is connected to a bus 108, and this bus is connected through a resistor 110 of high value to the junction point 92.

One end of the relay coil 100 is connected directly to the bus 94, while the other end is connected through a wire 112 to one of the contacts 84. The other contact 84 is connected through a wire 114 to the junction point 92.

A capacitor 116 is connected between the wire 108 and the bus 94. Additional capacitors 118 are arranged to be switched into parallel with the capacitor 116 by means of switches 120.

The capacitor 116 normally is charged from the rectifier 88 through the high resistance 110. When a key is depressed, and the type bar 36 is thrown toward the full line position of Fig. 2, in the manner previously described, the switch contacts 84 are brought into engagement. This causes energization of the relay 98, and causes the armature 104 to close against the fixed contact 96. This causes the capacitor 116, and any of the capacitors 118 that might be switched into the circuit, to be discharged substantially instantaneously through the electromagnet coil 74. This causes the poles 70 to exert a sudden and powerful attractive force on the slug 44, and thereby to press the type face 42 against the ribbon 34 to form a typing impression on the paper 32. Since this magnetic force is not applied until such time as the type face is in engagement with the ribbon, or very nearly so, the type face acts to form the typing impression with a pressing force.

It will be appreciated that the resilient strip or leaf spring 78 is tensioned by engagement of the roller 80 by the slug 44. The condenser or capacitor 116 discharges substantially instantaneously, and cannot recharge instantaneously due to the resistor 110. Accordingly, immediately upon formation of the typing impression, the spring or strip 78 straightens out by virtue of its resiliency, and starts the type bar back past the dashed line position of Fig. 2 toward its initial position as shown in Fig. 1. Release of the key 54 allows the key lever 50 to return to its initial position under the influence of spring 58, and the jack or dog 60 thereby snaps under the shoulder 67. It will be appreciated that the size of the resistor 110 is chosen so that the capacitor 116 readily will recharge in the time between strokes of a typist's fingers, but will not recharge sufficiently rapidly to preclude return of a key bar 36 toward its initial position under the influence of the leaf spring or resilient strip 78.

It will be apparent that greater force is needed to make typing impressions of a predetermined quality with some characters than is necessary with other characters. For example, the very small area of the period type face does not require nearly the force for making an impression than the large area of other characters, for instance the letter "w," requires. Thus, means is provided for varying the strength of the magnetic pressing action in accordance with the force required. More specifically, with reference to Fig. 5, there will be seen a type bar 36a having the type head or pallet 40a and type face 42a. For purposes of illustration, it will be presumed that the character of the type face 42a presents a larger area than that of the type face 42 in Fig. 1. The magnetically susceptible slug 44a held in place by the dovetail 46a accordingly is larger. Since the slug is larger, a greater magnetic force is exerted on it, and the type face 42a is pressed against the ribbon with

greater force than is the type face 42, whereby a uniform impression is obtained. By this means, a degree of control is exerted over the impression forming force without requiring extensive differences among the type bars and type heads or pallets. It will be understood that the dovetails form a force fit, or that other means are provided to lock the magnetic slugs in place so that they will not be displaced laterally from the type bar by engagement with the tapered guiding surfaces 72 of the magnet poles 70 in the event that a type bar should be bent.

A modification of the invention is shown in Figs. 6-9. In this form of the invention, only a single magnetic pole is used, and by this means the magnetic force can be made to centralize the type head or pallet. Many of the parts are similar to those previously shown and described, and similar numerals are utilized with the addition of the suffix *b*. Thus, the type bar 36b remains substantially the same as previously described, including the type head or pallet 40b, the type face 42b, and the magnetic slug 44b which may be held in place by the dovetail 46b. An abutment shoulder 122 is provided on the type bar substantially at the junction with the type pallet, and immediately below the magnetic slug 44b.

The electromagnet 68b in this case comprises a magnetizable core 124 mounted on a fixed part of the machine, and including the coil winding 74b. The core has only a single pole 70b, and as will be observed particularly in Fig. 7, this pole tapers to a narrow face 126 of substantially the same width as the slug 44b, it being understood that this slug is of the same width as the type pallet or head. Accordingly, when the pole tip 126 is magnetized, it centralizes the slug 44b, and hence centralizes the type face 42b.

The flexible switch blades 86b carrying the switch contacts 84b are mounted behind the magnetizable core 124, and may be supported therefrom by means such as a nonmagnetic support 127. Alternatively, the switch blades can be supported from any fixed part of the machine.

The magnetizable core is provided opposite the abutment shoulder 122 with at least one pair of lugs or ears 128. These lugs or ears fit within the channel sides 130 of a square switch actuator 132 surrounding the core. The switch actuator rides on the lugs or ears 128, and is provided with front and rear cross pieces 134 and 136 respectively. Coil springs 138 are compressed between the lugs or ears 128 and the front cross member 134 to urge the square actuator forwardly, such movement being limited by abutment of the rear cross member 136 against a nonmagnetic stop 140 on the back of the magnet core 124. The front cross member 134 is positioned for engagement by the shoulder 122, and a switch engaging insulated member 82b is mounted on the rear cross member 136 for engagement with the forward one of the switch blades 86b.

Accordingly, when the type bar 36 is pivoted in the same manner as heretofore disclosed, the shoulder 122 engages the square actuating member 132 and presses it backwardly against the force of the springs 138, thereby causing the switch engaging member 82b to deflect the switch blades 86b, thereby effecting contacting of the switch contacts 84b. This causes the circuit through the relay coil 100b to be closed in the manner previously described. As set forth heretofore, this causes energization of the relay coil 74b, and the magnetism of the pole 70b attracts the type bar and type head or pallet through the magnetic slug 44b, whereby to form a typing impression. Immediately upon discharge of the capacitor or condenser the springs 138 start the type bar back toward its rest position.

In accordance with the embodiments of the invention heretofore shown and described, a spring element is stressed by the type bar, and imparts movement to the type bar to return it toward its normal position. In Figs.

10 and 13 there is shown a system wherein a positive return impulse is applied electromagnetically. In this form of the invention, most of the physical parts remain as previously described. Thus, there is a type bar 36c having a type head or pallet 40c with a type face 42c thereon, and carrying a magnetic slug 44c.

The slug 44c engages the upper end of a lever 142 pivoted at 144 on a fixed part of the machine, and carrying one of the switch contacts 84c. Pivoting of the lever moves this switch contact 84c into engagement with the other switch contact 84c, thereby completing the circuit in the manner previously described. The lower end of the lever 142 is pivotally connected at 146 to the plunger 148 of a solenoid 150.

The wiring diagram of Fig. 13, accompanying Fig. 10, is similar to that shown in Fig. 4, and operation thereof will be obvious. In connection with this diagram, it will be seen that the capacitor 116c is charged through the resistor 110c and the armature 104c is pulled down against the contact 96c by energization of the coil 100c upon discharging of the capacitor by closing the contacts 84c. This causes instantaneous energization of the coil 74c, whereby a typing impression is formed. The solenoid 150 is connected in parallel with the coil 74c through a delay circuit 152 of any known or suitable design. Therefore, very shortly after the formation of the typing impression, the solenoid 150 is energized. This causes pivoting of the lever 142, and the type bar 36c is positively started back toward its initial position.

Reference previously has been made to varying the size of the slug, as 44, 44a, in order to vary the force for forming a typing impression. In some instances it might not be desirable to change the external size of the slug, and in such instances a slug may be used as shown in Fig. 11. In Fig. 11, the parts are similar to those previously shown and described, and include a type bar 36d having a type head or pallet 40d with a type face 42d thereon. The difference resides in the magnetic slug 44d, held in place by the dovetail 46d, in that the slug is provided with bores 154. The size of the bores, and also the number thereof, may vary from one slug to another, thereby varying the volume of the slug, and hence the magnetic force exerted thereon.

The slug also may be varied as shown in Fig. 12, wherein the parts just enumerated again are shown, this time with the addition of the suffix *e* to the identifying numeral. The distinguishing feature in this instance is that the front of the slug 44e is toothed or corrugated as at 156 in order to reduce the volume of the slug. It will be understood that in some instances it might be desirable to vary the external size of the slug, while boring of the slug, or toothing or otherwise externally shaping the slug might be desirable, and that all of these features might be used at the same time on different ones of the type bars of a typewriter constructed in accordance with the principles of this invention.

In accordance with all of the foregoing, various means are provided for electromagnetically producing a typing impression. Means is shown in Fig. 14 for also producing carriage advance without the addition of any substantial amount of structure. More particularly, Fig. 14 again shows the electromagnetic structure 68f, similar to that previously described, having the poles 70f, the strut 76f mounting the leaf spring or resilient strip 78f having the roller 80f at the upper end thereof, and the energizing coil 74f wound on the electromagnet. The distinguishing feature in this instance is that the core of the electromagnet has a recess 158 formed in one side thereof. A bell crank 160 is pivoted near the electromagnet 68f at 162 and is provided with a magnetically susceptible slug 164 capable of movement into the recess 158. The opposite end of the bell crank is pivotally connected at 166 to a link 168 which is connected to the carriage advance mechanism in place of the usual universal bar. It will be understood by those skilled in the art that the universal

bar is struck by the operating mechanism during a typing operation. In this instance the universal bar is replaced by the link 168. Accordingly, each time a typing impression is made by energization of the electromagnet, the slug 164 is attracted into the recess 158, thereby effecting a pull on the link 168, and operation of the carriage advance. It will be appreciated that provision must be made for carriage advance by the spacer bar, and accordingly the spacer bar is provided with a switch 170 (Fig. 4) in parallel with the switch contacts 84. Thus, whenever the spacer bar is actuated to close the switch contacts 170, the relay 98 will be operated, and the capacitor 116 will be discharged to energize the electromagnet 68, thereby pivoting the bell crank 160, and operating the carriage advance.

In accordance with a preferred form of this invention, means also is provided for electromagnetically returning the carriage. Such means is shown in Figs. 15 and 16. In this instance, the electromagnet structure 68g has been modified somewhat, having a pair of straight side arm core portions 172 carrying the poles 70g. The side arm portions are connected by a tubular magnetic section 174, and a magnetic core or plunger 176 is mounted within the hollow portion 174. A tubular end cap 178 carries a compression spring 180 which urges the plunger 176 to the right. However, the plunger is normally held inside the hollow portion 174 by a catch or detent 182. The catch or detent comprises a plunger retractable into a solenoid 184 against the force of a biasing spring (not shown) when the solenoid is energized by closing of switch contacts 186. These switch contacts are closed by a special key or the like provided on the typewriter in place of the usual carriage return lever. Alternatively, this mechanism can be utilized in addition to the usual manual carriage return.

On the outer end of the plunger 176 there is provided a hook 188 yieldable in a clockwise direction (Fig. 16) against the force of a spring 190. When the plunger is moved outwardly under the influence of the spring 180, the hook 188 snaps over one arm 192 of a lever 194 pivoted at 196 on a fixed part 198 of the machine. The opposite arm 200 of the lever is provided with a retractable tip 202 urged outwardly by a spring 204, and this retractable tip is engageable with rack teeth 206 which may be formed directly on the carriage, or which may be connected through suitable linkage, including the possibility of a flexible cable, or other suitable means. In addition to the snapping of the hook 188 over the lever arm 192, the outer end of the plunger 176 engages one of a pair of flexible switch blades 207 to force contacts 208 carried thereby into engagement. The switch contacts, as may be seen in Fig. 4, are connected in parallel with the contacts 84 and the contacts 170, whereby to energize the coil 74g of the electromagnet structure 68g.

When the carriage has advanced as far as is desirable, and the typist desires to return the carriage, all that is necessary is to actuate the button or lever to close the switch contacts 186. This causes retraction of the detent 182, and the plunger 176 is released. This causes the plunger to be expelled by the spring 180, and the hook 188 engages the arm of the lever 194 as aforesaid, the switch contacts 208 simultaneously being closed. This effects discharge of the capacitor 116 through the relay coil 74g, and the plunger 176 is snapped back to its initial position. This causes pivoting of the lever 194, and causes the carriage to be started rapidly toward its return position. The spring loaded arm 202 of the lever allows the tip of the lever to move along a linear path, and to remain in engagement with the rack teeth 206 over a substantial "throw." The "throw" will not be enough, in most cases, to move the carriage completely to its returned position, but such returning will be accomplished by inertia of the carriage. In this connection, it will be appreciated by those skilled in the art that a typist does not keep her hand on the manual return lever until the carriage is completely returned, but

rather imparts a snap action to the carriage that causes it to reach fully returned position by virtue of the inertia thus imparted to it.

A modification of the invention for returning the carriage when used with a single pole magnet such as in Fig. 6 is shown in Figs. 17-19. The parts in this instance are equivalent to those just described with regard to Figs. 15 and 16, in most instances, and similar numerals are used with the addition of the suffix *h*. Extended description therefore is believed unnecessary. Most particularly, the magnet core 124h is provided with a relatively movable plunger section 176h which is normally pulled outwardly by a spring 180h. This normal outward pull is resisted by a detent 182h operated in the manner described above. When the detent 182h is retracted, the plunger portion 176h of the core flies outwardly under the influence of a spring 180h to close the switch contacts 208h, the hook 188h engaging the arm 192h of the lever 194h. Closing of the switch contacts 208h causes energization of the coil 74h in the manner aforesaid, and this causes the plunger portion 176h to be drawn back toward the fixed core part 124h, the lever 194h thereby being pivoted to cause the carriage to be returned.

It will be observed that in this form of the invention, in order to provide for operation of the switch contacts 84h and to provide for return of the type bar toward its initial position, a small lever 209 is mounted on the front of the magnet core 124h by means of a pivot 210. The upper end of this lever is magnetic, and the lower end is non-magnetic. The upper end of this lever is struck by the shoulder 122h on the type bar as will be apparent particularly in Figs. 17 and 19, and this effects pivotal movement of the lever 209 sufficiently to cause the tail thereof to engage the switch contacts 84h carried by the flexible arms 86h, whereby the switch contacts 84h are closed, and the core 124h, 176h is magnetized by the coil 74h. This causes a typing impression by attraction on the magnetic slug 44h, and further causes additional pivoting of the lever 209, the upper end thereof being attracted by the upper end of the core 124h, to load a spring 212 stretched between the core and the tail of the lever. As soon as the capacitor has been discharged through the coil 74h, the magnetizing force of the core 124h dissipates, and the spring 212 pivots the lever 209 back toward its initial position, thereby starting the type bar 36h back toward its rest position.

In order to preclude noise in operation, a nylon or other satisfactory washer 214 is interposed between the coil 74h and a stop 216 on the core portion 176h. Similarly, nylon pads are placed on the core 124h at 218, and on the tip of the lever 209 at 220.

As will be understood, all parts within magnetic range of the electromagnet, and not specified or implied as being magnetic or magnetically susceptible, are made of non-magnetic materials.

From the foregoing it will be apparent that many advantages are possessed by the novel electromagnetic typewriter herein disclosed. The effort required for the operation of this novel typewriter will be on a par with that required by present electric typewriters, but it will retain the virtues of the "touch" of a conventional typewriter. This typewriter will be exceedingly quiet in operation due to the pressing nature of the type impression forming operation as compared with the usual slapping motion. There is no continuously running motor, which, if not noisy at first, will tend to become noisy with wear. The machine will be less costly to manufacture than present electric typewriters due to its simplicity, the elimination of an electric motor, and due to the reduced effort of assembly brought about by the fewer parts. Since the shock and vibration inherent in conventional manual and electric machines is greatly reduced, the entire chassis of the typewriter may be of lighter and less expensive design. Similarly, the type bars can be made

less rigid. This reduction of shock and vibration furthermore will lead to longevity of the typewriter and to substantially lowered repair bills, and to lack of fatigue of the typist.

The character of this machine is such that all printing stresses are confined to the type heads. This is partially responsible for the reduction of shock and vibration as noted heretofore. Damage to type bars through inadvertent striking of two or more keys simultaneously is unlikely since very little force is applied to the type bars until they reach the electromagnet, and the magnet can supply power to only one type bar at a time.

High speed of operation is possible since little manual effort is required, the "throw" of the type bars may be quite short (since the energy for printing is not stored in the inertia of the type bar) and a shorter throw means less travel time, and the lighter weight construction of the entire type bar linkage, from key to type face, leads to less inertia, and consequently faster operation.

Due to the constant power of the electromagnet, the typing impressions will be uniform, whereas many typists find it difficult to form uniform impressions with the usual manual machine. Furthermore, by expedients such as changing the number of capacitors in the circuit, the power of the electromagnet can be adjusted to compensate for the number of carbon copies to be made.

An important structural feature is that the switch for the electromagnet is operated by any type bar during a typing operation. Accordingly, no problems of synchronization or linkage adjustment are presented. The use of the single electromagnet for forming typing impressions, and also for effecting carriage escapement, and for effecting carriage return is of considerable importance.

It is to be understood that the illustrative embodiments of the invention as herein shown and described are capable of variation without departure from the spirit of the invention. Accordingly, it is to be understood that all variations such as fall within the spirit and scope of the appended claims form a part of this invention.

The invention is claimed as follows:

1. In a typewriter having an impression-forming area, a movably mounted type bar having a type face thereon, and a key for moving said type bar to a position adjacent said impression-forming area, the combination comprising an electromagnet operable on said type bar when said electromagnet is energized and having an iron core positioned beyond the path of movement of said type bar for attracting said type bar to urge the type face thereof toward said impression-forming area to form a typing impression, a switch closed by said type bar as it approaches said impression-forming area, and electrical circuit means interconnecting said switch with said electromagnet upon closing of said switch to energize said electromagnet.

2. In a typewriter having an impression-forming area, a movably mounted type bar having a type face thereon, and a key for moving said type bar to a position adjacent said impression-forming area, the combination comprising an electromagnet having a generally U-shaped iron core with a pair of confronting poles positioned for said type bar to pass between said poles, said electromagnet being operable upon energization thereof to act on said type bar to urge the type face thereof toward said impression-forming area to form a typing impression, switch means closed upon operation of said key and type bar as a type bar is positioned adjacent said impression-forming area, and electrical circuit means interconnecting said switch means with said electromagnet to energize said electromagnet upon closing of said switch means.

3. In a typewriter having an impression-forming area, a movably mounted type bar having a type face thereon, and a key for moving said type bar to a position adjacent said impression-forming area, the combination comprising an electromagnet having an iron core with a pole with which said type bar is brought into alignment and toward which said type bar moves, said electromagnet being oper-

able upon energization of said electromagnet to attract said type bar toward said pole and to urge the type face of the type bar toward said impression-forming area to form a typing impression, a switch closed upon operation of said key and type bar to energize said electromagnet as said type bar is positioned adjacent said electromagnet, and electrical circuit means interconnecting said switch with said electromagnet to energize said electromagnet upon closing of said switch.

4. In a typewriter having a platen, a pivotally mounted type bar having a type face thereon, and a key for pivoting said type bar toward said platen, the combination comprising an electromagnet operable on said type bar upon energization of said electromagnet to urge the type face thereof toward said platen to form a typing impression, a capacitor, electrical circuit means for charging said capacitor, switch means closed upon movement of said type bar toward said platen, and electrical circuit means operable upon closing of said switch means to discharge said capacitor through said electromagnet, thereby impulsively energizing said electromagnet.

5. In a typewriter as set forth in claim 4, the combination further comprising a plurality of capacitors, and means for selectively connecting all capacitors beyond said first capacitor into circuit with the first capacitor for varying the strength of the impulse applied to the type bar.

6. In a typewriter having a platen, a plurality of pivotally mounted type bars having a type face thereon, and a plurality of keys for individually pivoting said type bars toward said platen, the combination comprising an electromagnet for individually acting on said type bars as they are pivoted toward said platen, said electromagnet being operable when energized to urge an adjacent type face toward said platen to form a typing impression, a capacitor, electrical circuit means for charging said capacitor, a common switch engageable by any of said type bars upon pivoting thereof toward said platen, and electrical circuit means interconnected with said switch and operable upon closing thereof to effect discharging of said capacitor through said electromagnet, thereby impulsively to energize said electromagnet.

7. In a typewriter having a platen, a plurality of pivotally mounted type bars each having a type face thereon, and a plurality of keys for individually pivoting said type bars toward said platen, the combination comprising an electromagnet operable on any of said type bars when pivoted toward said platen, means for varying the electromagnetic effect of said electromagnet on said type bars in accordance with the character of said type face to produce a uniform typing impression from one type face to another, said electromagnet being effective when energized to urge an adjacent type face toward said platen to form a typing impression, switch means operable upon approach of a type bar towards said platen, and electrical circuit means interconnecting said switch means with said electromagnet for energizing said electromagnet upon operation of said switch means.

8. In a typewriter having a platen, a carriage advance mechanism, a plurality of pivotally mounted type bars each having a type face thereon, and a plurality of keys for individually actuating said type bars toward said platen, the combination comprising an electromagnet individually operable on one of said type bars pivoted toward said platen by its key, said electromagnet when energized acting on a type bar so pivoted to urge the type face thereof toward said platen to form a typing impression, switch means closed by operation of any key and type bar, electrical circuit means interconnecting said switch means with said electromagnet for energizing said electromagnet upon closing of said switch means, and means attracted toward said electromagnet upon energization thereof for operating said carriage advance mechanism.

9. In a typewriter having a platen, a carriage carrying said platen, a plurality of pivotally mounted type bars each having a type face thereon, and a plurality of keys for individually pivoting said type bars toward said platen, the combination comprising an electromagnet electromagnetically operable on any one of said type bars pivoted toward said platen, said electromagnet when energized being effective to urge the type bar electromagnetically operated on toward said platen to cause the type face thereof to form a typing impression, switch means closed by movement of any key and type bar, electrical circuit means interconnecting said switch means with said electromagnet for energizing said electromagnet upon closing of said switch means, a part attracted toward said electromagnet upon energization thereof for effecting return of said carriage, means normally holding said part against movement in response to such attraction, a carriage-return key, and means operatively interconnecting said carriage-return key and said holding means for selectively releasing said holding means to free said part for movement thereof by attraction toward said core whereby to effect return of said carriage.

10. In a typewriter as set forth in claim 9, the combination wherein the electromagnet comprises a core, and wherein the part attractable to effect return of the carriage comprises a movable part of said core.

11. In a typewriter having a carriage and a platen carried thereby, a plurality of pivotally mounted type bars each having a type face thereon, and a plurality of keys for individually pivoting said type bars toward said platen, the combination comprising an electromagnet having a core, said electromagnet being operable one at a time on any type bar pivoted toward said platen, said electromagnet when energized being effective to urge the type face of such type bar toward said platen to form a typing impression, switch means operated upon movement of any key and corresponding type bar, electrical circuit means interconnecting said switch means with said electromagnet to energize said electromagnet upon closing of said switch means, a movable core part operable upon energization of said electromagnet to effect return of said carriage, means normally holding said part against movement in response to such attraction, a carriage-return key, means operatively interconnecting said carriage-return key and said holding means for selectively releasing said holding means to free said part for movement thereof by attraction toward said core whereby to effect return to said carriage, and a part attracted toward said core upon energization of said electromagnet to effect advance of said carriage.

12. In a typewriter as set forth in claim 11, the combination further comprising capacitor means connected in said circuit by said switch means for impulsively energizing said electromagnet.

13. In a typewriter having a platen, a movably mounted type bar having a type face thereon, and a key for moving said type bar toward said platen, the combina-

tion comprising an electromagnet operable on said type bar upon energization of said electromagnet to urge the type face thereof toward said platen to form a typing impression, a capacitor, electrical circuit means for charging said capacitor, switch means closed upon movement of said type bar toward said platen, and electrical circuit means operable upon closing of said switch means to discharge said capacitor through said electromagnet, thereby impulsively energizing said electromagnet.

14. In a typing machine having an impression-forming area, a movably mounted type member having a type face thereon, a magnetically susceptible part on said member and a key for moving said type member into position adjacent said impression-forming area, switch means closed upon such movement, electrical circuit means energized by such closing, and an electromagnet connected in said circuit and energized upon energization of the circuit, said electromagnet having an iron core with pole means complementary to and accommodating said magnetically susceptible part of said member to urge said type face toward said impression-forming area to form a typing impression.

15. In a typewriter having a platen, a plurality of pivotally mounted type bars each having a type face thereon, and a plurality of keys for individually pivoting said type bars toward said platen, the combination comprising an electromagnet operable on said type bars one at a time when said electromagnet is energized to urge the type face of the type bar acted upon toward said platen to form a typing impression, a single switch closed by any of said type bars as it approaches said platen within range of said electromagnet, electrical circuit means interconnecting said switch with said electromagnet upon closing of said switch to energize said electromagnet, means for terminating energization of said electromagnet to release a type bar for return to initial position, and electromagnetic means for starting movement of a type bar back toward its initial position.

16. In a typing machine having an impression-forming area, a movably mounted type member having a type face thereon, and a key for moving said type member into position adjacent said impression-forming area, the combination comprising an electromagnet operable on said type member upon energization of said electromagnet to urge the type face thereof toward said impression-forming area to form a type impression, a capacitor, electrical circuit means for charging said capacitor, switch means closed upon movement of said type member into position adjacent said impression-forming area, and electrical circuit means operable upon closing of said switch means to discharge said capacitor through said electromagnet, thereby impulsively energizing said electromagnet.
